MECHANICAL BRUSHING DEVICE AND
MOTOR THEREFOR

William S. Sussman, New York, N. Y.

Application March 6, 1940, Serial No. 322,578

5 Claims. (Cl. 185—37)

This invention relates to new and useful improvements in brushing devices adapted to be driven by a motor, and relates more particularly to an improved self-contained source of power comprising a spring motor.

One of the objects of the present invention is to provide a novel mechanical tooth brush having a moveable brushing element adapted to be driven by a self-contained prime mover positioned within the handle of the device, the brushing element being detachably mounted on a moveable member and arranged in such a manner that it may be readily detached when it becomes worn through use and a new one inserted in its place.

Another object of the invention is the provision of an improved rotary brushing device, adapted particularly for brushing the teeth, wherein the bristles are mounted on a revolvable core in such a position as to enable the user to derive the maximum brushing effectiveness with a motor of minimum power.

One of the principal objects of the invention is to provide a novel spring motor of relatively small dimensions and being capable of storing considerable energy therein in order that the motor may deliver an unusual amount of power for a fair period of time.

The present motor is designed particularly for operating mechanical razors, tooth brushes, and the like, as well as flashlights and other small articles. The relationship of the parts, including the spring and the train of gears, is such that the whole motor will occupy a very little space and fit conveniently within the hand of the user.

Another object of the invention is to provide a small self-contained prime mover which is driven by a spring and includes a train of gears and governor structure so positioned relative to the spring as to leave the major portion of the motor housing free to accommodate a spring of considerable size.

A still further object of the invention is the provision of a spring motor wherein substantially the full measure of power stored in the spring by manual winding thereof, will be effectively delivered to the driving gears.

Fig. 1 is a vertical section taken through the preferred embodiment of the present device, the section being taken on line 1—1 of Fig. 2. Fig. 2 is a side elevation of the device with one cover portion removed. Fig. 3 is another vertical section taken through the device, such section being on line 3—3 of Fig. 2, the figure also showing a modified form of spring-winding mechanism. Fig. 4 is a horizontal section taken on line 4—4

of Fig. 1. Fig. 5 is a vertical section taken on line 5—5 of Fig. 2, the view showing the interior of the governor structure. Fig. 6 shows a modified winding means.

The preferred embodiment of the invention comprises opposed frame portions 10 and 11 made preferably from sheet metal, and they are desirably joined at their upper ends by means of a horizontal frame portion 12. This horizontal portion is formed with an aperture (not shown) through which a vertical shaft 15 passes, such shaft being journaled in a bearing member comprising a bearing portion 16 positioned below upper frame portion 12, and another bearing portion 17 rigidly mounted on the upper surface thereof. At the upper end of this bearing portion 17 a sleeve 18 is secured, such sleeve having a gear housing 19 rigidly mounted at the upper end thereof.

The gear housing contains conventional gearing (not shown) adapted to transmit motion from vertical shaft 15 to a substantially frustro-conically shaped brushing element having a curved outer terminal portion 21', the brushing element being particularly adapted for tooth-brushing purposes. This brush is formed with a core 20 having a plurality of bristles 21 mounted therein. The core may, if desired, be formed in the identical shape of the brushing element 21 with tapered side walls and a convexly curved forward end wall, as shown in Fig. 1, appropriately reduced in size, of course, and in this instance the bristles disposed over the tapered side walls of the core and over the curved outer or free end thereof will all be of substantially uniform length. If desired, however, the core may be substantially cylindrical in shape and the desired shape of the conical brushing element obtained by merely trimming the ends of the bristles to produce the shape illustrated in Fig. 1. The bristles are preferably positioned at an angle to the radius of the core, the brushing element preferably revolving in the direction indicated by the arrow in Fig. 2. The brush is desirably removably mounted on a rotating spindle 22 and may be secured thereto by any conventional means, such as projections 23 carried by the brush which are received in recesses in spindle 22.

If desired a suitable eccentric cam may be positioned at the upper end of shaft 15 to impart reciprocating and oscillating movement to the brush, rather than rotative movement.

The opposed vertical frame portions 10 and 11 are maintained in their spaced relation by means of a plurality of bolts 24 having heads 25, which

pass through aligned apertures adjacent to the marginal edges of such frame members, each bolt carrying a spacer sleeve 21.

Opposed frame portions 10 and 11 are further formed with a plurality of aligned apertures which serve as bearings for a plurality of shafts, shaft 29 being journaled adjacent to the lower end of the frame. A flat clock-type spring 30 is secured at its inner end to such shaft 29 by means of a pin 31, and at its outer end the spring is secured to the interior surface of a substantially cylindrical spring housing 33 by means of a pin 34. A gear 37 of slightly greater diameter than the external diameter of housing 33 is secured to such housing and constitutes the main drive gear of the motor. This gear is freely mounted for rotation on shaft 29.

The spring is wound by means of manual rotation of shaft 29, this being accomplished by means of a hand-winding lever 39 which is pivotally mounted on extension 40 of shaft 29 at its right-hand end when viewed in the position shown in Fig. 2. At its opposite end shaft 29 projects beyond frame member 10, as shown at 42 (Fig. 2), and carries a conventional circular toothed ratchet wheel 43, the teeth of such wheel being engaged by a pivoted pawl 45 which is urged against the wheel by means of a spring 46 (Fig. 2). The teeth of large gear 37 engage the teeth of a small gear 50 mounted on a shaft 51 which is journaled adjacent to one terminal in frame member 10. This shaft is journaled at its opposite end in a suitable aperture in a substantially rectangular bearing plate 54. This plate is supported in a position spaced from frame 10 by means of screws 56 carrying spacer sleeves 57.

Another plate 58 substantially triangular in shape is also carried by such screws and is inwardly spaced from plate 54. Shaft 51 carries another and larger gear 60 which drives a smaller gear 62 carried on uppermost transverse shaft 63, such shaft being journaled at its terminals in frame members 10 and 11. Likewise keyed to shaft 63 is a beveled gear 65 which engages a somewhat smaller beveled gear 66 carried at the lower end of shaft 15.

Thus it will be apparent that large gear 37 on spring housing 33 drives small gear 50 on shaft 51, and large gear 60 likewise carried thereon drives small gear 62 keyed to shaft 63, which in turn drives beveled gear 65. Also keyed to shaft 63 is a gear 67 of considerable size which engages a small gear 68 mounted on a counter shaft 69, such shaft being journaled in bearing plates 54 and 58. Shaft 69 likewise carries a somewhat larger gear 72 which drives a small gear 74 carried on governor shaft 75, which latter shaft is journaled at one end in frame member 11, and at its other end in bearing plate 54.

The governor comprises a cup-shaped member 78 carrying a collar 79 which is keyed to shaft 75 by means of pin or set screw 80. A pair of curved governor arms 84 are pivotally mounted at one end thereof 85, on circular portion 86 of cup 78. Each governor arm is provided with a piece of felt or other resilient material 88, and outer terminal 90 of each arm is connected with the adjacent pivot 85 by means of a small coil spring 91. As cup 78 is rotated through rotation of shaft 75, the outer terminals 90 of these governor arms tend to move outwardly through centrifugal force, and the resilient portions 88 carried on the arms engage the inner surface of a

small cup 93 positioned within cup 78 and secured to frame member 11.

Inward movement of governor arms 84 is limited by means of pins 94. The motor is held 5 against rotative movement by means of a lever 95 which is centrally pivoted at 96, one end of such lever having a piece of felt or other similar material 97 secured thereto, such portion being normally urged against the exterior of cup 78 by means of spring 99. The lever is adapted to be moved by finger-engaging portion 100 which moves the opposite end of arm 95 away from cup 78, thus permitting operation of the motor.

The sides of the motor are closed by means of 15 a substantially U-shaped housing portion 102, the upper terminals of which are secured to the lower surface of frame portion 12 by means of screws 103.

A modification in the winding mechanism is 20 shown in Fig. 6 wherein a large, bevelled gear 105 is keyed to shaft 29 (not shown), such gear being engaged by a small bevelled gear 106 mounted on a vertical shaft 108 at the lower end of the casing, such shaft carrying a winding cap 107 at its lower end.

It will be apparent that the brushing element 25 shown in Figs. 1 and 2 may be varied in size and shape since, in some cases, the front of the brush may have the principal brushing surface rather than the side, as in the embodiment illustrated. 30 Also, if desired, other means for detachably securing such brush to the rotating spindle may be employed, or the entire sleeve 18 may be made removable. The prime mover for operating the 35 brushing element may constitute a motor driven by electricity or other power, and may be provided with a rotating shaft or merely an oscillating movement, as desired.

The spring motor illustrated and described may 40 also be varied without departing from the appended claims. It will be apparent, however, that by taking the energy from the outer terminal of the spring and delivering it to a main drive gear, such being the first of a train of speed-multiplying gears positioned closely adjacent to 45 one side wall of the casing, a maximum amount of energy is imparted to the work adapted to be performed by the motor. For most purposes the governor shaft is preferably driven more rapidly than the final drive shaft and such governor shaft driven by speed multiplying gears starting at said final drive shaft. In cases however 50 wherein a higher speed is desired in the motor, such can be accomplished by varying the size of gears 37, 60 and 65, and in such case the governor 55 may be positioned on shaft 63.

What I claim is:

1. A spring driven power unit for a motor 60 driven tooth brush having a tapered rotary brushing element, said power unit comprising a casing, a manually rotatable winding pin journaled within the casing adjacent to its lower end, a flat coiled spring carried thereby and being secured at its inner end to the pin, a spring 65 housing freely journaled on the pin, the outer end of the spring being anchored to the casing, a primary driving gear carried by the housing, a drive shaft operatively connected with the brushing element journaled adjacent to the upper end of the casing, a plurality of trains of speed multiplying gears between the driving gear and the drive shaft, a governor shaft, a speed governor carried thereby, and a plurality of speed multiplying gear trains between the drive shaft and the governor shaft to impart higher speed of ro-

tation to the governor shaft than to the drive shaft, said governor including a circular member keyed to the shaft, a plurality of arms pivotally mounted at one end thereof on the member, spring means for restraining outward movement of the opposite ends of the arms due to centrifugal action, and an annular member fixed within the casing relative to the arms and engageable by the arms as the speed of rotation increases.

2. A spring driven power unit adapted to be held in the hand of the user and comprising a casing including a pair of spaced frame members, a manually rotatable winding shaft journalled between such frame members adjacent to their lower ends, a flat coiled spring carried thereby and being secured at its inner end to the shaft, a substantially cylindrical housing carried on the shaft and enclosing the spring, said spring being secured at its outer end to the housing, the spring occupying substantially the entire area between the frame members, a primary driving gear carried by the housing, a driven shaft journalled adjacent to the upper end of the frame members, and a plurality of trains of speed-multiplying gears between the primary gear and the driven shaft, a governor shaft and a train of speed-multiplying gears between the driven shaft and the governor shaft, a governor carried by the latter shaft and including a plurality of arms pivotally mounted at one end thereof on the governor, the opposite ends of the arms being urged inwardly by means of a coil spring, and a drive shaft operatively connected with the driven shaft and projecting from the casing.

3. A spring driven power unit adapted to be held in the hand of the user and comprising a casing including a pair of spaced frame members, a manually rotatable winding shaft journalled between such frame members adjacent to their lower ends, a flat coiled spring carried thereby and being secured at its inner end to the shaft, a substantially cylindrical housing carried on the shaft and enclosing the spring, said spring being secured at its outer end to the inner surface of the housing, the spring occupying substantially the entire area between the frame members, a primary driving gear carried by the housing, a driven shaft adjacent to the upper end of the frame members, and a plurality of trains of speed-multiplying gears between the primary gear and the driven shaft, a governor shaft and a plurality of trains of speed-multiplying gears between the driven shaft and the

governor shaft, a cylindrical governor carried by the latter shaft, a fixed cup positioned within the governor, a pair of arms pivotally mounted within the governor adapted to bear against the cup to reduce the speed of the governor shaft, and a manually releasable brake normally engaging the governor.

4. In a motor driven tooth brush, the combination of a casing including a pair of spaced, elongated frame members adapted to be held in the hand of the user, a winding shaft journalled adjacent to the lower end of the frame, a primary driving gear freely journalled on said shaft, a coiled, flat spring carried concentrically of said shaft and being secured thereto at its inner end, the outer end of the spring being operatively connected with the driving gear, a driven shaft journalled adjacent to the upper end of the frame, a governor shaft and a rotating governor carried thereby, and a train of speed-multiplying gears between the spring and the driven shaft, and between the driven shaft and the governor shaft, a sleeve projecting upwardly from the casing, a shaft positioned therein, gears connecting said shaft with the driven shaft, a rotary brushing element journalled at the upper end of the sleeve, and gears connecting the brushing element with the shaft in the sleeve.

5. In a motor driven tooth brush, the combination of a casing including a pair of spaced, elongated frame members adapted to be held in the hand of the user, a winding shaft journalled adjacent to the lower end of the frame, manual winding means carried by said shaft externally of the casing, a substantially cylindrical spring housing freely journalled on said shaft, a coiled, flat spring carried concentrically of said shaft and being secured thereto at its inner end, the outer end of the spring being connected with said housing, a driven shaft journalled adjacent to the upper end of the frame, a governor shaft and a rotating governor carried thereby, and a plurality of trains of speed-multiplying gears between the spring and the driven shaft, and between the driven shaft and the governor shaft, a sleeve projecting upwardly from the casing, a drive shaft positioned therein, gears connecting said shaft with the driven shaft, a rotary brushing element journalled at the upper end of the sleeve at substantially right angles to the drive shaft, gears connecting the brushing element with the drive shaft, and a releasable brake normally restraining rotation of the governor.
